UNITED STATES PATENT OFFICE.

DWIGHT P. MONTAGUE, OF CHATTANOOGA, TENNESSEE, AND ULYSSES GRANT LEE, OF CHICAGO, ILLINOIS, ASSIGNORS TO MONTAGUE MAILING MACHINERY CO., A CORPORATION OF TENNESSEE.

ADDRESS-PLATE AND INDEX-TAB THEREFOR.

1,110,221.

Specification of Letters Patent. Patented Sept. 8, 1914.

Substitute for application filed October 3, 1911, Serial No. 652,605. Renewed June 14, 1913, Serial No. 773,759. This application filed January 9, 1914. Serial No. 811,272.

To all whom it may concern:

Be it known that we, DWIGHT P. MONTAGUE, residing at Chattanooga, Tennessee, and ULYSSES GRANT LEE, residing at Chicago, Illinois, citizens of the United States, have invented certain new and useful Improvements in Address-Plates and Index-Tabs Therefor, of which the following is a specification.

10 Our invention relates to printing plates for use in addressing and mailing machinery, and particularly to an index tab combined with the said plate. In applying this index tab, we modify the construction of the 15 plate from that heretofore employed, such, for instance, as in the American patent of Charles Owens, #939,739, of November 9, 1909, and U. G. Lee, #982,076, January 17, 1911.

20 One object of the present invention is to provide a tab that will not, in any way, interfere with the handling of the plate, and is not liable to be damaged or bent, and for this purpose the index tab is substantially wholly within the limits of the 25 plates shown in the said patents, not projecting beyond the contour of said plates.

A further object is to provide such a 30 form of index tab and a way for associating it with the plate that it will be supported firmly by the plate which affords a backing for the tab throughout its entire length.

A still further object is to provide such 35 a form of index tab and way of attaching it to the plate that the tab will not become separated from the address plate accidentally, but may be readily withdrawn from the plate or connected with said plate when 40 desired.

Other objects of the invention will appear hereinafter, and the invention consists in the features hereinafter particularly pointed out and claimed.

45 In the accompanying drawings, Figure 1 is a rear view of the plate or a view of that side opposite to that upon which the embossed letters are raised, the tab being shown in place; Fig. 2 is a cross sectional view of the plate on the line 2-2 of Fig. 1, looking from the left of said figure; Fig. 3 is a longitudinal sectional view through one of the depressed and reinforced

edges of the plate with the tab in place therein; Fig. 4 is a detail view of the tab 55 separated from the plate; Fig. 5 is a perspective view of the corner of the address plate showing the turned or rolled edge with its recess, and with the cut away portion and holding projection. 60

In this drawing, 1 is the printing plate composed of metal adapted to be embossed to form the letters for printing the address. This plate has its margins depressed, or in other words, located in a plane to one 65 side of the main portion of the plate, and these margins are bent back or rolled upon themselves as indicated at 1'. The index tab, as shown in Fig. 4 consists of a plate preferably of metal adapted to receive the 70 index marking on its face, the said plate having an extension 2, and this is adapted in size to fit within the space 3 formed by rolling or turning the edge of the margin of the plate back upon itself. The extension 2 of the index tab is suitably bent, as shown in Fig. 4, to secure a spring contact 75 effect with the inner walls of the rolled or turned margin of the plate. This margin is cut away at 4, as shown in Fig. 1, or 80 partly cut away, to provide a space in which the main portion of the index plate containing the marking may lie. There is left, however, an intact portion of this margin up to the dotted line 5 in Fig. 1, and this 85 furnishes a backing for the main part of the index tab which, with its main portion, overlies this part of the flange or margin which is not entirely cut away. At the extreme end of this bearing or backing 90 portion of the margin a projection 6 is left on the plate, and when the index tab is seated in place its edge abuts against this projection, which thus acts to retain the index tab in position. The index tab, when 95 being thrust into position, will slide over this projection, and having arrived at proper position, its edge will snap in rear of the projection and will thus be retained in place, it being understood that the index 100 tab has a certain degree of resiliency, being formed of metal. We do not wish to limit ourselves, however, in this respect, as the index tab may be held by friction alone.

It will be observed that the index tab is 105 located wholly within the original contour

of the plate, its upper edge being in line with the edge of the margin of the plate, and its end edge lying within the plane of the end edge of the address plate. The 5 rolled margin of the plate forms, in effect, a pocket for receiving the shank or extension of the tab.

The term "terminal" as used by us is to distinguish the opening or mouth leading 10 to the interior of the hollow rolled margin from the recess in the plate formed by the cutting away or omission of a part of the rolled edge.

We claim as our invention:

15 1. An address plate having a rolled marginal portion provided with a terminal opening axially in line with the recess in the margin, and a tab having a portion inserted in the terminal opening and extending longitudinally from the terminus of the rolled margin within the recess formed by the said rolled margin, substantially as described.

2. An address plate having a turned or 25 rolled margin cut away at one point and presenting a terminal opening axially in line with the recess within the rolled margin and a tab located at the cut away portion of the margin and having a portion inserted in 30 said terminal opening and extending lengthwise of and within the rolled margin, substantially as described.

3. In combination with an address plate having a rolled margin cut away at one 35 corner of the plate presenting an opening, and an index tab held at said cut away corner removably by a portion thereof inserted in the said opening and extending lengthwise of the plate, substantially as described.

4. In combination with an address plate having a rolled margin partly cut away presenting a terminal opening axially in line 45 with the recess in the said margin, and a tab held by the rolled margin and being located wholly within the line of the outer edge of the plate extended, substantially as described.

5. In combination an address plate having 50 a rolled margin cut away at one point presenting a terminal opening axially in line with the recess within said margin and a

tab having a part inserted in the said terminal opening and extending longitudinally of the recess in the margin, the other 55 part of said tab occupying the cut away part and overlapping a portion of the plate which forms a backing therefor.

6. In combination with an address plate having a turned or rolled edge open at one 60 end, a tab having a bent extension inserted in the end opening of the turned edge and extending lengthwise thereof, substantially as described.

7. In combination with an address plate 65 having a rolled margin terminating short of the end of the plate, presenting an end opening, said plate having a projection at its end having a recess between it and the end of the rolled margin, an index tab having a portion 70 fitting in the opening of the rolled margin and with its main portion engaged by the projection, substantially as described.

8. In combination an address plate having 75 a main portion to form an impression surface, and a margin offset to one side of the main part of the plate, said margin being turned upon itself providing a recess therein and cut away at one point presenting a terminal opening axially in line with 80 the recess in the margin, and a tab occupying the space left by the cut away portion and having an extension entering the said recess in the turned margin by which the tab is held in place, substantially as described. 85

9. An address plate having a rolled margin provided with a terminal opening axially in line with the recess in the margin and a tab having a portion inserted in the terminal opening, said plate having a bearing for the end of the tab to retain the same in place, substantially as described. 90
